DESIGN FOR A COMBINED HANDBAG AND COSMETIC HOLDER

Arthur R. Botham, New York, N. Y., assignor to Coty, Inc., Wilmington, Del., a corporation of Delaware

Application January 28, 1942, Serial No. 105,466

Term of patent 14 years

To all whom it may concern:

Be it known that I, Arthur R. Botham, a citizen of the United States, residing in the city and State of New York, have invented a new, original, and ornamental Design for a Combined Handbag and Cosmetic Holder, of which the following is a specification, reference being had to the accompanying drawing, forming a part thereof.

In the drawing:

The design for the combined handbag and cosmetic holder disclosed is characterized by the cosmetic holder having the configuration best shown in Fig. 4.

I claim:

The ornamental design for a combined handbag and cosmetic holder as shown and described.

ARTHUR R. BOTHAM.
